(57) **CLAIM**

The ornamental design for a hip and ridge end cap, as shown and described.

DESCRIPTION

FIG. 1 is a perspective view of a hip and ridge end cap in accordance with our design;

FIG. 2 is another perspective view of the hip and ridge end cap in accordance with our design;

FIG. 3 is a front elevation view of the hip and ridge end cap in accordance with our design;

FIG. 4 is a side elevation view of the hip and ridge end cap in accordance with our design;

FIG. 5 is another side elevation view of the hip and ridge end cap in accordance with our design;

FIG. 6 is a back elevation view of the hip and ridge end cap in accordance with our design;

FIG. 7 is a top plan view of the hip and ridge end cap in accordance with our design;

FIG. 8 is a bottom plan view of the hip and ridge end cap in accordance with our design; and,

FIG. 9 is a cross-sectional view, taken along section lines 9—9 in FIG. 2, of the hip and ridge end cap in accordance with our design.

The broken lines showing environmental structure are for illustrative purposes and form no part of the claimed design.
